UNITED STATES PATENT OFFICE.

LEO STEIN, OF ROCHESTER, NEW YORK, ASSIGNOR TO THE STEIN MANUFACTURING COMPANY, OF SAME PLACE.

DESIGN FOR A BURIAL-CASKET LID.

SPECIFICATION forming part of Design No. 17,245, dated April 5, 1887.

Application filed January 6, 1887. Serial No. 223,624. Term of patent 14 years.

To all whom it may concern:

Be it known that I, LEO STEIN, of Rochester, in the county of Monroe, in the State of New York, have invented a new and useful Design for Metallic Burial-Casket Lids, of which the following, taken in connection with the accompanying drawings, is a full, clear, and exact description.

My invention relates to designs for metallic coffin or burial-casket lids; and the invention consists in the herein-described design, which will be described in connection with the accompanying drawings, and pointed out in the claim.

Figure 1 is a top plan view of my newly-designed metallic coffin-lid. Fig. 2 is an inverted view of the foot portion, and Fig. 3 shows a modification in the arrangement of the figures of the design, these three views being deemed necessary to fully illustrate my design.

The leading feature of my design consists in the figured surface of the foot portion of the lid, which, when viewed in elevation, presents the appearance of a series of figures embossed or indented in the metal of the lid, so as to give the appearance of hamfered or relief work.

A represents the metallic lid, composed of the head-section B and foot-section C, having, respectively, rounded ends *b c*, and the rim *a* extending around the entire edge of the lid. The head-section portion B is flat, as is best

illustrated in Fig. 1, while the foot portion C may be arched, oval, flat, or inclined, as desired. The said foot portion has formed upon it figures *d d d*, said figures being either embossed or indented in the metal in series throughout the foot-section portion C, so that in connection with the flat portion B the lid presents to the eye the combined effect of the smooth head portion and a figured foot portion, and gives a very pleasing effect when combined with the rounded ends *b c*.

The figures *d d* may be of geometrical forms, as stars or polygons, or plain cup-shaped figures, so long as they are arranged in series over the foot portion of the lid.

Having thus fully described my design, what I claim as new, and desire to secure by Letters Patent, is—

In a design for a burial-casket lid herein shown and described, the smooth head-section B, having rounded end *b*, and the foot-section C, having figures *d d* and the rounded end *c*, substantially as shown and described.

In testimony whereof I have hereunto signed my name, in the presence of two attesting witnesses, at Rochester, in the county of Monroe, in the State of New York, this 22d day of December, 1886.

LEO STEIN.
